United States Patent Office

Des. 200,809
Patented Apr. 6, 1965

200,809

JUG

Richard L. Platte, Ann Arbor, Mich., assignor to Hoover
Ball and Bearing Company, Saline, Mich.

Filed June 29, 1964, Ser. No. 80,636

Term of patent 14 years

(Cl. D58—5)

FIG. 1

FIG. 2

FIG. 3

FIG. 4

FIGURE 1 is a side elevational view of a jug showing my new design;

FIGURE 2 is a rear elevational view thereof;

FIGURE 3 is a front elevational view thereof; and

FIGURE 4 is a top plan view thereof.

The dominant features of my design reside in the portions shown in full lines.

I claim:

The ornamental design of a jug, as shown and described.
